DESIGN FOR A GARMENT

Isidor Krosney, Brooklyn, N. Y., assignor to Oxford Pants Co., Inc., a corporation of New York

Application January 10, 1934, Serial No. 50,365

Term of patent 7 years

To all whom it may concern:

Be it known that I, ISIDOR KROSNEY, a citizen of the United States of America, and a resident of Brooklyn, in the county of Kings and State of New York, have invented a new, original, and ornamental Design for Garments, of which the following is a specification, reference being had to the accompanying drawing forming a part hereof. In the drawing:

Fig. 1 is a front view of the garment, and
Fig. 2 is a back view of the garment.

The garment is characterized by a mid-front portion simulating part of a vest, leg-receiving bifurcations below, and a skeleton back above the seat portion.

I claim:

The ornamental design for a garment substantially as shown and described.

ISIDOR KROSNEY.
